CONTROL MECHANISM FOR GAS DRIVEN
WELDERSEdward A. Hobart, Troy, Ohio, assignor to The
Hobart Bros. Company, Troy, Ohio, a corpora-
tion of Ohio

Application May 16, 1932, Serial No. 611,628

7 Claims. (Cl. 290—40)

My invention relates to an automatic throttle control for engines, particularly internal combustion engines; and it is my object to provide such a control in connection with arc welders.

5 It is my object to provide an automatic throttle control for an engine which will be delayed in its action. When used in connection with an arc welder it is desired to provide a time interval after the arc is broken during which there will be no reduction in speed of the engine to give an opportunity to change electrodes, but if it is desired to have the arc broken for a longer interval, then the speed of the engine will be automatically cut down by an automatic adjustment of the throttle.

10 15 It is my object to eliminate the use of vacuum actuating means in this connection.

It is my object to eliminate the engine as a source of power and it is my object to eliminate the generator and its circuit as a source of power 20 for controlling the throttle.

In particular it is my object to provide a source of power independent of both the engine and the generator for controlling the mechanism that adjusts the throttle and thereby have such an adjustment accurately performed without being affected by either the engine or the generator.

Referring to the drawing, I have illustrated diagrammatically the control of my invention.

In detail, 1 indicates an exciter armature having an exciter field 2. 3 designates the welder main field while 4 designates the main field rheostat of the welder. 5 is the welder armature having a commutating field 6 and a diverter field 7. 8 is the stabilizing reactance of the welder. 9 is an ammeter and 10 is a volt meter for measuring the characteristics of performance of the welder. An electrode circuit is connected into the welder at the terminals 11. 12 indicates an electrode and 12a a work piece in circuit with the welder 40 circuit for the purpose of arc welding.

I provide a sensitive relay 13 connected to the lines 13a and 13b into the welder circuit, which is a sensitive relay normally closed. The switch member affected thereby designated 14a is arranged through the wires 14b and 14c in circuit with the battery 14. In this circuit is a throttle operating a relay comprising a coil 15, and a core 15a connected to the dash pot 16 which so regulates its movement as to give the necessary delay 45 in order to permit of the change of electrodes before cutting down the engine speed. Connected to the core 15a is a bell crank 17, one end of which has connected thereto a spring 17a. A pitman 17b connects the bell crank 17 to the throttle 18 of the engine 19.

In operation the switch member 14a is held against the relay 13 so that the battery circuit from the battery 14 is open, but upon breaking the arc, the switch member 14a is held to close the battery circuit to the battery 14 and comprises a 60 coil 15 by reason of its being in circuit.

This tends to actuate the core 15a and dash pot 16, but such actuation movement is delayed by the dash pot action for a period sufficient in time to permit of the change in electrodes. If the 65 electrodes are changed or for some other reason the arc is re-established within a suitable time limit, the system will again be restored to arcing position, switch 14a will be open and the engine will not be slowed down.

70 However, if a greater delay is incurred so that the dash pot passes through a cycle of operations and ceases to retard the movement of the butterfly valve 18, that valve will close and the engine will be shut down to idling speed.

75 I desire to comprehend within my invention such modifications as may be clearly embraced within the claims and scope of my invention.

Having thus fully described my invention, what I claim as new and desire to secure by Letters 80 Patent, is:

1. In combination, a driving power source, a throttle therefor, a driven power source and a third power source for actuating the throttle, said third power source being rendered operative 85 by the driven power source upon the driven power source being rendered inoperative, whereby the third power source will reduce the speed of the driving power source.

2. In combination, an engine, a generator driven thereby, a throttle on the engine, a battery and battery circuit controlling said throttle, and means operated by the generator for rendering the battery circuit inoperative while the generator is producing a welding arc and to cause 95 said battery to operate the engine throttle when the generator is not producing an arc.

3. In combination, an engine, a generator driven thereby, a throttle on the engine, a battery and battery circuit controlling said throttle, and means operated by the generator for rendering the battery circuit inoperative while the generator is producing a welding arc and to cause 100 said battery to operate the engine throttle when the generator is not producing an arc, and means of delaying that action a predetermined time after the breaking of the arc.

4. In an internal combustion engine, a throttle therefor, an independent source of power adapted to actuate said throttle, a welding generator driv- 110

en by said engine, means operated by the generator of rendering said independent source of power inoperative while the generator is furnishing a welding arc and rendering it operative when it is not furnishing such a welding arc.

5. In combination in an internal combustion engine, a throttle therefor, means normally to maintain said throttle open, a dash pot connected thereto to delay the closing of the throttle, a relay for operating said throttle and dash pot, a battery for operating said relay, including a battery circuit, a switch operated by the welding generator for opening and closing said battery circuit and a welding generator circuit adapted to open said battery circuit when the generator is furnishing an arc and permit the battery circuit to close when the generator is not furnishing an arc.

6. In combination in an internal combustion engine, a throttle therefor, means normally to maintain said throttle open, a dash pot connected thereto to delay the closing of the throttle, a relay for operating said throttle and dash pot, a bat-

tery for operating said relay, including a battery circuit, a switch operated by the welding generator for opening and closing said battery circuit and a welding generator circuit adapted to open said battery circuit when the generator is furnishing an arc and permit the battery circuit to close when the generator is not furnishing an arc, said generator having associated therewith an exhaustive relay adapted to actuate said battery circuit switch.

7. In combination, an internal combustion engine, a throttle therefor normally open, electrically operated means for closing said throttle, a dash pot for resisting said closing and an independent electric power source for actuating said throttle closing means, a switch therefor operated by the welding generator, a welding generator and its circuit for producing an arc, a relay circuit associated with the welding generator circuit having a relay adapted to actuate said switch when the generator is furnishing an arc.
